L. M. PERSONS
EXERCISING APPARATUS

1,896,010

Filed Nov. 6, 1929

Fig. 1.

UNITED STATES PATENT OFFICE

LAWRENCE M. PERSONS, OF ST. LOUIS, MISSOURI, ASSIGNOR TO THE EMERSON ELECTRIC MFG. CO., OF ST. LOUIS, MISSOURI, A CORPORATION OF MISSOURI

EXERCISING APPARATUS

Application filed November 6, 1929. Serial No. 405,074.

This invention relates to improvements in exercising apparatus, and more particularly to a cabinet and mounting for an apparatus of that class.

5 An object of the invention is to provide a support for the motor and operating parts of an exercising apparatus of the vibrating belt type, which constitutes a compact housing for the apparatus when not in use 10 and which may be extended to provide a rigid support for the apparatus when the same is adjusted for use.

The detailed advantages of the construction will be apparent from the following 15 description, taken in connection with the accompanying drawing in which

Fig. 1 is a front elevation of the apparatus adjusted for use.

Fig. 2 is a vertical section substantially on 20 the line 2—2 of Fig. 1.

Fig. 3 is a view substantially on the same line, showing the apparatus in the folded or closed adjustment. Fig. 4 is a detail view similar to Fig. 2.

25 In the embodiment of the invention illustrated in the drawing the cabinet is shown as comprising a housing formed from sheet metal. The side walls 1 and the back wall 2 may be conveniently formed from a single 30 sheet of metal having the free front edges turned in laterally and then backwardly to form the vertical side posts 3. The bottom wall 4 is united to the bottom edges of the side and back wall, and rectangular top facing members 5 are mounted along the top edges of the side walls 1. These parts assembled as described constitute a rigid housing having a front and top opening. The front opening is closed by a front wall 6 having inturned side flanges 7. The member 6 is hinged to the side posts 3 at its lower end, so that it may be moved outwardly to form an obliquely inclined platform extending forwardly from the housing when the apparatus 40 is in open adjustment and, when the apparatus is in closed adjustment, may be folded upwardly to complete the vertical walls of the closed housing.

The bottom of the cabinet is supported by 45 feet 8 at the four corners. The outer face

of the member 6 carries at its free extremity a plurality of feet 9 extending transversely across the same near the edge thereof. The feet 9 are preferably in the form of rubber rings attached to the member 6 by screws or bolts.

The member 6 carries transversely of its inner face and near its free edge a plate 10 having a roughened or knurled surface constituting a foot piece on which the user of the apparatus may stand when operating the same.

A frame 11, in the form of a U-shaped strap, is mounted within the housing and constitutes a transverse and lateral brace. A 65 bracing construction is provided, comprising a rectangular plate 12 hinged to the flanges 7 of the member 6 and to links 13 extending from the frame 11 to a point beyond the upper edge of the plate 12. The links 13 are connected respectively by pivots 14 to said frame 11 and to a rod 15 extending transversely between the downwardly extending flanges 16 of the plate 12. A contractile spring 17 is connected at one end adjacent to the back 70 wall of the housing and at the other end to the rod 15, the tendency of said spring being to retract the rod 15 rearwardly and thereby draw the toggle connection between the links 13 and the rod 15 over center. The construction just described provides a toggle lock 75 when the platform 6 is in extended adjustment, the arrangement being such that when the platform is in extended adjustment the point of bearing of the load will be on the rear feet of the housing and upon the feet 9 of the platform. This adjustment raises the front feet 8 from a horizontal surface and forms a bridge so that the cabinet will be relatively free from vibration, even though the supporting floor upon which the cabinet may be mounted may be slightly uneven or irregular.

The outer face of the plate 12 is preferably 85 provided with a knurled foot rest 18 for the user of the apparatus when the apparatus is used in seating position, the operator bracing his feet against the upper portion of the plate 12 on the foot rest 18, thereby tending to hold the cabinet rigid.

In closing the front wall of the cabinet it is only necessary for the operator to grasp the upper edge of the plate 12 and break the toggle lock, whereupon the member 6 will 5 be automatically drawn into closed adjustment by the action of the spring 17.

Lugs 19 are provided on the inner face of the posts 3 near the top thereof, and constitute abutments for arresting the inward 10 movement of the upper free edge of the member 6. Openings 20 are preferably formed in the side walls 1 immediately below the members 6 and provide hand holes for conveniently engaging the cabinet for moving 15 it from place to place.

Within the bottom portion of the housing there is formed a triangular-shaped chamber comprising an inclined wall 21 and a vertical wall 22, which chamber provides a 20 convenient receptacle for the leads to the motor. The top of the cabinet is closed by a lid formed from a flat plate 23 having a down turned flange 24 around its front and side walls. The lid is hinged to the members 25 5 near the back of the housing so that it may be raised and lowered to open or closed adjustment.

The operating portion of the exercising apparatus may be of any convenient construction. As shown, it comprises a motor 25 supported on a base plate 26 hinged adjacent to the rear of the housing on the hinge pins supported by the inner vertical wall of the members 5. The motor 25 supports a bearing 35 bracket 27 within which a shaft 28 is journaled for rotation and having eccentric crank arms 29 on its opposite ends. A vibrating belt 30 is attached to the crank arms in a known manner. The shaft 28 is driven by 40 any known driving connection enclosed in a housing 31 and not shown in detail as the form thereof is well known.

There is a transverse horizontal member 32 supported across the top opening of the 45 housing. This member constitutes a rest for the base plate 26 of the vibrating apparatus when the apparatus is in open position. Since the base 26 is hinged in or near the top of the housing, it may be moved to a lowered 50 position, as shown in Fig. 3, by swinging the operating parts of the apparatus downwardly and inwardly into the housing, or it may be adjusted in the upwardly extended position shown in Figs. 1 and 2. When in the 55 upper adjustment the base 26 is arranged to be locked by a plate 33, the lower end of which extends over a lug 34 on the rear edge of the base 26, considered from the position when the operating part of the apparatus is 60 in position for operating adjustment. A spring 35 is attached to the inner face of the lid 23 and to a lug 36 on the base 26. The spring 35 tends to draw the lid 23 forwardly and to cause the end of the plate 33 to engage over the rear edge 34 of the plate 26, 65

thereby latching the base in position. When it is desired to drop the operating portion of the apparatus it is necessary only to exert rearward pressure on the upper edge of the lid 23, which disengages the latch and permits the operating mechanism to be swung inwardly into the housing, whereupon the spring 35 functions to close and hold the lid in closed adjustment. 70

The power leads for the motor are in a cable 37 that enters through the back wall of the housing, and the switch leads 38 connect into the motor and lead to a point for convenient operation by the operator in starting the motor. The chamber formed by the walls 21-22 constitutes a convenient receptacle for the cable 38 and for that portion of the cable 37 that extends within the housing. 75

While I have described the invention in detail, I do not desire to be understood that I limit myself to exact construction shown and described, but what I claim and desire to secure by Letters Patent is:— 80

1. In an apparatus of the class described, a cabinet having one of its vertical walls hinged and its top wall hinged, a plate hingedly connected to said vertical wall, links intermediate said plate and the cabinet and pivoted to the cabinet and to said plate forming with the plate toggle links, and a spring having one end connected to one of said toggle links and the other end connected to a fixed part of the cabinet, arranged and adapted to cause the toggle links to act as a lock in one position of the plate and to automatically raise the vertical wall in another position of the plate. 90

2. In an apparatus of the class described a cabinet, having one of its vertical walls hinged, a plate connected to said hinged wall, links intermediate said plate and the cabinet and pivoted to the cabinet and to said plate forming with the plate toggle links, and a spring having one end connected to one of said toggle links and the other end connected to a fixed part of the cabinet, arranged and adapted to lock the links and plate to form a toggle lock between the cabinet and said vertical wall in one adjustment and to automatically raise said wall in another adjustment. 100

3. A cabinet for exercising apparatus having one vertical wall thereof arranged for downward and outward movement, a toggle brace between said wall and the cabinet, and a spring having one end connected to the toggle brace and the other end to the cabinet, arranged and adapted to operate said toggle brace to hold the same in locked adjustment when said wall is in open position and to move the wall to closed position when said toggle lock is manually broken. 110
